(**) Term: **14 Years**

Primary Examiner—Mitchell I Siegel

(21) Appl. No.: **29/332,642**

CLAIM

(22) Filed: **Feb. 20, 2009**

The ornamental design for a golf club head, as shown and described.

(51) **LOC (9) Cl.** 21-02
(52) **U.S. Cl.** D21/747
(58) **Field of Classification Search** D21/747-751,
D21/759; 473/324-331, 350

See application file for complete search history.

DESCRIPTION

(56) **References Cited**

FIG. 1 is a top perspective view of a golf club head;
FIG. 2 is a bottom perspective view of the golf club head of FIG. 1;

FIG. 3 is a front elevational view of the golf club head of FIG. 1;

FIG. 4 is a rear elevational view of the golf club head of FIG. 1;

FIG. 5 is a top view of the golf club head of FIG. 1;

FIG. 6 is a bottom view of the golf club head of FIG. 1;

FIG. 7 is a toe end view of the golf club head of FIG. 1; and,
FIG. 8 is a heel end view of the golf club head of FIG. 1.

The broken lines shown in one or more of the figures are for illustrative purposes only and form no part of the claimed design.
